UNITED STATES PATENT OFFICE.

WILLIAM HARMAN HOWELL, OF THOROLD, ONTARIO, CANADA, ASSIGNOR
TO WILLIAM WILKESON, OF YOUNGSTOWN, NEW YORK.

PULP-GRINDER.

SPECIFICATION forming part of Letters Patent No. 314,844, dated March 31, 1885.

Application filed October 9, 1884. (No model.)

To all whom it may concern:

Be it known that I, WILLIAM HARMAN HOWELL, of Thorold, in the county of Welland, Province of Ontario, Dominion of Canada, have invented a new and Improved 5 Pulp-Grinder, of which the following is a full, clear, and exact description.

My improvements relate to a pulp-grinding mill in which the running stone is of conical 10 form and is surrounded by a fixed stone of corresponding shape; and the invention consists in the construction and arrangement of parts, as will be hereinafter fully described and claimed.

Reference is to be had to the accompanying 15 drawings, forming part of this specification, in which similar letters of reference indicate corresponding parts in both the figures.

Figure 1 is a vertical section of a pulp- 20 grinder with my improvements, and Fig. 2 is a horizontal section on line $x x$ of Fig. 1.

The conical running stone A is clamped by 25 nuts between flanges a on spindle b, and the hollow conical bed-stone B is within a metal casing, c, that is bolted upon a circular spout, d, that forms the middle frame of the machine, supported on legs e. To the top of casing c are attached bridge-trees f, that carry the upper bearing, g, of the spindle. The 30 lower end of the spindle rests in a step, h, that is sustained by a cross-bar, i, and tightening-screws k, which are provided with hand-wheels l, so that the step and spindle can be raised and lowered. The step h is a hollow sleeve 35 carrying steel disks for the spindle to bear on, and the step in turn bears on the center m, the latter bearing being at the upper part of the sleeve, so as to prevent tipping. The step is within a box, n, that is sustained by hangers o from spout d. The driving-pulley p is 40 within the hangers o, and is attached to the spindle by a feather-key, so as to allow end movement of the spindle through the hub of the pulley. At q, on the upper bridge-trees, 45 f, is a cross-bar that limits the upward movement of the spindle.

The hopper r is attached on casing c, and is formed on its sides with inclined or curved flanges s, that act to force the material into the space between the upper edges of the 50 stones.

The runner A is made with curved furrows t, and the stationary stone has similar furrows running in opposite directions to furrows t.

At u is a pipe for supplying a chemical 55 solution to the hopper.

The mill is also provided with water-supply pipes.

Having thus fully described my invention, I claim as new and desire to secure by Letters 60 Patent—

1. A pulp-grinder consisting, essentially, of the conical running stone A, shaft b, to which said stone is clamped, the fixed stone B, surrounding the said running stone, the casing c, 65 surrounding the fixed stone, spout d, secured to the lower edge of said casing, the hangers o, secured to the under side of spout d, cross-bar i, the vertically-adjustable rods k, connecting the outer ends of the cross-bar with the 70 frame above said cross-bar, steps h in the hangers o, center m between the step and cross-bar i, pulley p on the shaft b within the hangers o, the bridge-trees f, mounted on top of casing c and provided with the bearing 75 g, and cross-bar q, bearing on the upper end of shaft b to prevent vertical movement thereof, and a hopper, r, substantially as set forth.

2. The combination, with the conical running stone A and the hollow conical fixed 80 stone surrounding the same, of the hopper r, provided with the vertical inclined flanges s, extending from the top to the bottom of the hopper and acting to force the material into the space between the stones, and the pipe u, 85 for directing a stream of water between the stones to cool them, substantially as set forth.

WILLIAM HARMAN HOWELL.
